(57) **CLAIM**

The ornamental design for a light fixture as shown and described.

DESCRIPTION

FIG. 1 is a top perspective view of a light fixture;

FIG. 2 is a bottom perspective view thereof;

FIG. 3 is a front view thereof;

FIG. 4 is a top view thereof; and,

FIG. 5 is a bottom side view thereof.

The right side view, left side view, and rear view are mirror images of the front view thereof.

The broken lines in the figures are for the purpose of illustrating an LED panel as the light source and form no part of the claimed design.

It is noted that the circle elements on the base of the light fixture are illustrated as solid black surface elements.
